[57] CLAIM

The ornamental design for an earpiece for use with
telephones, as shown and described.

DESCRIPTION

FIG. 1 is a perspective view of an earpiece for use with
telephones, showing my new design;
FIG. 2 is the front elevational view thereof;
FIG. 3 is the rear elevational view thereof;
FIG. 4 is a left side elevational view thereof, the right
side elevational view being identical thereto;
FIG. 5 is the top plan view thereof; and,
FIG. 6 is a bottom plan view thereof.

FIG. 1

FIG. 2

FIG. 3

FIG. 4

FIG. 5

FIG. 6
